UNITED STATES PATENT OFFICE.

GILBERT F. QUINN, OF REVERE, MASSACHUSETTS.

METHOD OF ATTACHING RUBBER AND LEATHER HEELS TO SHOES.

Application filed December 22, 1921. Serial No. 524,247.

To all whom it may concern:

Be it known that I, GILBERT F. QUINN, a citizen of the United States, residing at Revere, in the county of Suffolk and State 5 of Massachusetts, have invented a new and useful Method of Attaching Rubber and Leather Heels to Shoes, of which the following is a specification.

The object of my invention is to provide 10 a novel method for temporarily combining or assembling a rubber top lift and a leather or composition base in their proper position relative to each other so that the entire heel base and rubber top lift can be attached to the shoe in the shoe factory with 15 one nailing operation on the heeling machine.

In the accompanying drawings illustrating 20 my invention, Figure 1 is a perspective view of the heel applied to a shoe; Fig. 2 is a vertical section through the heel on line 2-2 of Fig. 1; and Fig. 3 is a similar section taken after the nails for securing the heel to the sole have been driven into place.

25 Like numerals designate like parts in each of the several views.

In carrying out my method of assembling the leather or fibre heel base 1 with the rubber top lift 2 I temporarily fasten the 30 two parts together with suitable metal or wooden pegs or tacks 3 from the inner surface of the base through into a portion of the rubber top lift as at 4, the top lift 2 being thereby held in its properly centered position until it is inserted into the heeling machine when the regular or usual rubber heel nails 5 are driven into their proper nail holes 6 in the rubber top lift and through the washers 7, as shown in Fig. 3, and going 35 40 through the entire mass, and thereafter being clinched, as at 8 on the inside of the shoe, as shown in Fig. 3, where the clinched ends 8 engage the sole 9.

The shoe manufacturer in the past has 45 been attaching the base with one operation and the rubber top-lift with another. In some shops they have been coating the base and then the top-lift with cement and then employing girls to assemble them together 50 which is expensive. Some rubber heel mak-

ers have been vulcanizing the two parts together for the shoe factory which is also much more expensive and unsatisfactory owing to the high percentage of imperfect heels which this method produces in 55 the rubber heel factory. My new method produces a perfect result of base and top-lift assembly in every instance with practically no additional expense of labor or equipment to the heel maker and therefore I believe it to be a new and novel method. Also, as I drive the temporary nails 3 from the inner surface of the base through into a portion of the rubber top-lift and not completely through said rubber top-lift, I do not 60 deface or mark the outer surface of the rubber top-lift in any way whatsoever, thus leaving the regular nail holes of the rubber top-lift free to receive the regular rubber heel nails which permanently fasten the entire mass to the shoe.

My heel is the only one known to the trade that can be attached by the heeling machine without the use of cement to make the edge of the rubber heel fit tight to the leather 70 base. All other types of rubber top-lifts now in use by the shoe factories must be cemented separately before they can be applied to the base.

Heretofore all rubber top-lifts known as 80 being of the concavo-convex type have been sold to the cobbler trade only for hand attaching as the heeling machine in the shoe factory cannot attach a rubber heel unless it lies flat. My new method of temporarily 85 nailing the rubber heel to the leather base, flattens this concavo-convex type of heel on the base thus opening a new and much larger trade to the maker of this style of heel, while still retaining the new improvement of 90 avoiding the use of cement to effect a tight joint between the rubber top-lift and the leather base.

What I claim is—

1. The method of attaching rubber and 95 leather heels to shoes, consisting in combining and assembling a rubber top lift and a leather or composition base in their proper position relative to each other by attaching means driven from the inner or top sur- 100

face of the base through and into a portion of the rubber top lift, and thereafter firmly securing both elements to the shoe.

2. The method of attaching rubber and leather heels to shoes, without the use of cement, consisting in securing the rubber heel to the leather base by pegs or nails

driven from the top of the base part way into the rubber heel, and thereafter nailing both the rubber heel and the leather base simultaneously to the shoe, and clinching the nails inside the shoe, substantially as described.

GILBERT F. QUINN.
